UNITED STATES PATENT OFFICE.

WILLIAM E. LEIGHTON, OF WEST PEMBROKE, MAINE.

REED-ORGAN.

SPECIFICATION forming part of Letters Patent No. 276,887, dated May 1, 1883.

Application filed July 29, 1882. (Model.)

To all whom it may concern:

Be it known that I, WILLIAM E. LEIGHTON, of West Pembroke, Washington county, Maine, have invented a new and useful Improvement 5 in Reed-Organs, of which the following is a full, clear, and exact description.

This invention relates to reed-organs and similar musical instruments, in which the wind-chest is constructed or provided with an upward extension for the purpose of giving an 10 increased resonance.

The invention consists in an upward extension of the main wind-chest provided with a partition, whereby the air in its way to the 15 bellows is made to circulate both up and down said wind-chest extension; and it also consists in a combination, with the upward wind-chest extension, of a resonant air-chamber arranged 20 in front of said extension. A reed-organ thus constructed has better resonance and a full ringing tone.

Reference is to be had to the accompanying drawings, forming part of this specification, in 25 which similar letters of reference indicate corresponding parts in both figures.

Figure 1 represents a broken front view of a reed-organ in part, having my invention applied; and Fig. 2, a vertical section on the line *x x* of the same.

30 A in the drawings indicates the main wind-chest of a reed-organ; B B, its suction or exhaust bellows; *b b*, the keys; *c*, the reeds, and *d* the valves by which the reeds are controlled. Mounted on the rear portion of the main wind-chest *A* is an upward extension, *D*, of said 35 wind-chest, the same forming a supplementary wind-chest extending throughout the length of the instrument, or thereabout, and constructed or provided with a diaphragm, *e*, arranged to extend to near the top of said extension *D* and down to the bottom of the main wind-chest *A*, leaving front and rear passages, *f g*, throughout the length of the supplementary wind-chest. The rear one, *g*, of these 40 passages connects with the bellows. The sides of the supplementary wind-chest and the diaphragm *e*, forming these passages *f g*, may be 45

made of thin wood, cloth, or any other suitable material or materials to give the requisite tone and effect.

In the working of the organ the air which passes through the reeds into the main wind-chest *A* is conducted up the passage *f* of the upward extension or supplementary wind-chest *D*, and, passing over the top of the partition *e*, 55 flows down the passage *g* to the bellows, thereby giving a full ringing tone. To improve the effect and augment the resonance of the instrument, however, I arrange in front of the supplementary wind-chest *D* a resonant air-chamber, *E*, arranged to extend along or across the instrument, and which may have any number of perforations *h* or other openings in it. This resonant chamber may be made of any suitable material, and serves to increase the 60 volume of sound given out by its front, which acts as a sounding-board.

Having thus described my invention, I claim as new and desire to secure by Letters Patent—

1. In combination with the main wind-chest, 70 reeds, and bellows or exhaust devices of the instrument, the upwardly-projecting supplementary wind-chest *D*, provided with a longitudinal diaphragm or partition, *e*, arranged to form passages to conduct the air from the 75 main wind-chest, after its passage through the reeds and on its way to the bellows, both upwardly and downwardly through the supplementary wind-chest, substantially as specified.

2. The combination, with the main wind-chest *A* and bellows *B*, of the upwardly-projecting supplementary wind-chest *D*, having a longitudinal partition, *e*, up within it, arranged to form upward and downward passages *f g*, 80 in communication below, respectively, with the main wind-chest and bellows, and the resonant air-chamber *E*, arranged in front of said supplementary wind-chest, substantially as 85 and for the purposes herein set forth.

WILLIAM E. LEIGHTON.
